HARVEY HUBBELL, OF BRIDGEPORT, CONNECTICUT.

SEPARABLE ATTACHMENT-PLUG.

1,021,101.

Specification of Letters Patent. Patented Mar. 26, 1912.

Application filed May 11, 1911. Serial No. 626,567.

To all whom it may concern:

Be it known that I, HARVEY HUBBELL, a citizen of the United States, residing at Bridgeport, county of Fairfield, State of Connecticut, have invented an Improvement in Separable Attachment-Plugs, of which the following is a specification.

This invention has for its object to simplify, cheapen and to generally improve the construction and operation of separable attachment plugs, to simplify the assembling, to perfect the insulation and especially to provide a structure in which the danger of breakage shall be reduced to the minimum should the plug as a whole or the cap be dropped.

With these and other objects in view I have devised the novel separable attachment plug of which the following description in connection with the accompanying drawing is a specification, reference characters being used to indicate the several parts.

Figure 1 is a longitudinal section of the plug complete, the parts being in the assembled position; Fig. 2 a transverse section on the line 2—2 in Fig. 1, looking in the direction of the arrows; Fig. 3 a plan view of the insulating guard disk detached; Fig. 4 a section on the line 4—4 in Fig. 3; Fig. 5 a plan view of the base with the shell removed; and Fig. 6 is an elevation of the base with the shell removed.

10 denotes the insulating base, 11 the screw shell; 12 the insulating cap and 13 the insulating guard disk. The cap is provided with the usual central hole 14 through which the wires (not shown) are passed and on its inner side with a recess 15.

16 denotes binding screws and 17 contact posts which are carried by plates 18 rigidly secured in the recess. The contact posts are slotted longitudinally as at 19 in order to give a spring action in engaging and are provided with circumferential grooves 20 to receive bosses on the contact tubes.

The base has an external screw thread 21 molded thereon which is engaged by the screw shell in the usual manner. For the base contacts, indicated by 22 and 23, I preferably use tubes which lie in longitudinal holes 24 in the base and are provided with inwardly projecting bosses 25 which are adapted to pass over the heads of the contact posts and to engage the grooves therein. The bosses in the tubes act at right angles

to the planes of the slots in the contact posts. The slots permit the posts to yield slightly as the members of the plug are moved together and to spring outward again when the bosses are seated in the grooves. Contact 22 serves as a center contact for a socket (not shown) and is carried by a bracket 26 held in place by a center screw 27. This contact lies wholly within one of the holes in the base and is thus perfectly insulated from the screw shell by the base itself. Contact 23 is carried by a bracket 28 which rests upon a ledge 29 on the base and is engaged by a flange 30 on the screw shell to which it is secured as by solder, at 35, after the screw shell is in place to lock the screw shell. The assembling is thus made very simple. (See Fig. 6 in connection with Fig. 1). The insulating guard disk is of greater diameter than the base and cap, is carried by the cap and lies between said members in the assembled position. This guard disk is in practice made of fiber and serves the double purpose of an insulating cover for the binding screws in the cap and also as a buffer to protect the plug as a whole and the cap when detached from breakage should it be dropped. The wires (not shown) act normally to prevent the outer face of the cap from striking should it be dropped and cause the blow to be received by the guard disk, which is of greater diameter and is relatively non-breakable. The guard disk is provided with holes 31 through which the contact posts pass and is retained in place by spring clamping plates 32 which are recessed into the guard disk and are provided with corresponding holes through which the contact posts pass. These clamping plates are provided with central longitudinal slots 33 which cross the holes for the contact posts, the holes being made slightly smaller than the posts so that the arms of the plates will grip the posts. The clamping plates are shown as secured in place by lugs 34 formed integral therewith which are passed through the guard disk and clamped on the under side.

The operation is the same as usual with separable attachment-plugs. The base is inserted in a socket, the screw shell engaging the shell of the socket (not shown). The insulating guard disk remains removably attached to the cap. Electrical connection is made by passing the contact posts into long

itudinal holes 24 in the base and moving them forward until the grooves in the posts are engaged by the bosses on the contacts in the base. The passage of the current is from the screw shell through bracket 28 and one of the contact posts to the corresponding binding screw in the cap and returning through the other binding screw and contact post and through contact 23 and bracket 26 which serves as a center contact for engagement with the contact of a socket (not shown).

Having thus described my invention I claim:

15. 1. A separable attachment plug comprising a cap having binding screws and contact posts, a base having a screw shell, contacts in said base, brackets by which said contacts are carried, one of said brackets being 20 retained in place by the screw shell and the second bracket serving as a center contact with a socket, a screw by which said second bracket is retained in place and an insulat-

ing guard disk intermediate the cap and the base.

2. In a separable attachment plug, the combination with a cap having a recess and binding screws and contact posts secured therein, of an insulating guard disk covering the recess and detachably secured to the 30 contact posts.

3. In a separable attachment plug, the combination with a cap having a recess and binding screws and contact posts secured therein, of an insulating guard disk covering the recess and provided with spring clamping plates through which the contact posts pass and by which the guard disk is secured to the cap.

In testimony whereof I affix my signature 40 in presence of two witnesses.

HARVEY HUBBELL.
